W. W. POTTS.
ADJUSTABLE ILLUMINATING FIXTURE.
APPLICATION FILED APR. 28, 1919.
1,327,733.

Patented Jan. 13, 1920.

UNITED STATES PATENT OFFICE.

WARREN W. POTTS, OF ELKHART, INDIANA.

ADJUSTABLE ILLUMINATING-FIXTURE.

1,327,733.

Specification of Letters Patent.

Patented Jan. 13, 1920.

Application filed April 28, 1919. Serial No. 293,206.

To all whom it may concern:

Be it known that I, WARREN W. Potts, a citizen of the United States, residing at Elkhart, in the county of Elkhart and State of Indiana, have invented certain new and useful Improvements in Adjustable Illuminating-Fixtures, of which the following is a specification.

The present invention relates primarily to illuminating fixtures, and particularly to adjustable hangers for electric illuminating fixtures.

The primary object of the invention is to provide an adjustable hanger for electric illuminating fixtures which is peculiarly adaptable for use in connection with center or domelike fixtures, which are usually suspended from the ceiling.

With this and other objects in view, the invention will be more readily understood upon reference to the accompanying drawing and following detailed description.

In said drawing—

Figure 1 is a vertical section showing a part of the electric fixture, *per se*, in elevation;

Fig. 2 is a cross-section on the line 2—2 of Fig. 1;

Fig. 3 is a cross-section on the line 3—3 of Fig. 1; and

Fig. 4 is an enlarged detailed view of the manner of connecting the telescoping conductor rods to the wiring of the fixture.

Referring to the drawing in detail, the invention primarily involves a center post 1, which is adapted to be suspended vertically from and affixed to the ceiling by means of the attaching block 2, which is secured to the post in any convenient manner, preferably by a screw-threaded connection. Slidably mounted on the post 1 is a supporting means for the light structure, consisting of the casing 3 having a block 4 secured in the upper portion thereof, which block is provided with a central opening to receive the post, and with two smaller openings on each side of the central opening to receive the casings 5 for the conductor rods 6, which extend through said casings and terminate near the lower end thereof in telescoping relation to the casings. These conductor rods pass through the block 2 and are insulated therefrom by means of the insulating sleeves 7, and are adapted to be connected to a suitable source of electricity. The casings 5 are insulated from the block 4 and the casing 3, and terminate with their ends connected to the wiring 8 of the light structure. This light structure may be of any conventional form, such as the inverted bracket 9, which is provided with a screw-threaded attaching collar 10 adapted to receive the threaded end 11 of the block 12, which is mounted in the lower end of the casing 3 and provided with suitable openings to receive the ends of the casings 5 in a similar manner as the block 4. The purpose of the invention is to enable the light structure to be raised or lowered without breaking the circuit, to which end the post 1 is adapted to telescope within the casing 3; likewise, the rods 6 being adapted to telescope within the casings 5, and as they are in contact therewith, the circuit will be completed through the rods and casings to the wiring 8 of the light structure. To enable any predetermined adjustment, or rather, selective adjustment of the light structure to be had and retained, a locking device is associated with the casing 3 and the post 1. This locking device consists of a pawl 13, pivotally mounted on a collar 14, which is in turn secured to the block 4 by suitable brackets 15. As the post 1 telescopes in the casing 3, the pawl is adapted to selectively engage any one of the notches 16 on the side of the post and lock the casing 3 with the post, whereby the light fixture which is carried by the casing 3 may be vertically adjusted. A rod 17 is attached to the pawl 13 and extends downwardly through the casing 3, the block 12 and the center of the light fixture, and terminates in a push button 18, which will enable the rod to be actuated to disengage the pawl from any one of the notches 16 and permit adjustment of the light fixture to be had. A suitable spring 19 is employed to exert the necessary downward tension on the rod 17 and retain the pawl 13 in locking relation to the notches. The extension of the rod 17 from the lower part of the light fixture is inclosed in a suitable casing 20, which carries a plug 21 on its lower end, with an opening 22 therein to provide a housing for the spring 19. In order to add a pleasing appearance to the construction, an outer casing 23 is used to telescope with the casing 3. This outer casing is secured to the usual canopy 24 which incloses the rods 6, block 2 and upper part of the post 1 and its associated parts. It is to be noted that the casing 3 is provided with

an extension 25, which is secured to the light fixture and enables the connection between the wiring 8 and the conductor casings 5 to be completely housed; also, that an annular ring 26 is provided to prevent the outer casing from marring the surface of the casing 3 when the same are telescoped. Furthermore, the end of the post 1 is constructed with an abutment 27 to prevent withdrawal 10 from the casing.

Claims:

1. An adjustable hanger for electric illuminating fixtures, comprising a fixed center post, a casing surrounding said post 15 adapted to telescope therewith, providing a support for the electric fixture, a pair of conductor rods mounted adjacent said post, a pair of tubes in said casing receiving said conductor rods and adapted to telescope therewith, said tubes being insulated from 20 said casing and providing a circuit completing means from the conductor rods to the electric fixture, said central post having an elongated notched portion along one of its 25 sides, and a dogging device carried by said casing adapted to selectively engage said notches, whereby the electric fixture may be vertically adjusted.
2. An adjustable hanger for electric illuminating fixtures, comprising a fixed center post, a casing surrounding said post 30 adapted to telescope therewith, providing a support for the electric fixtures, a pair of conductor rods mounted adjacent said post, 35 a pair of tubes in said casing receiving said

conductor rods and adapted to telescope therewith, said tubes being insulated from said casing and providing a circuit completing means from the conductor rods to the electric fixture, said central post having an 40 elongated notched portion along one of its sides, and a dogging device carried by said casing adapted to selectively engage said notches, whereby the electric fixture may be vertically adjusted, and an outer casing 45 surrounding the central post and the first-named casing in telescoping relation therewith.

3. An adjustable hanger for electric illuminating fixtures, comprising a fixed center 50 post, a casing surrounding said post adapted to telescope therewith, providing a support for the electric fixture, a pair of conductor rods mounted adjacent said post, a pair of tubes in said casing receiving said 55 conductor rods and adapted to telescope therewith, said tubes being insulated from said casing and providing a circuit completing means from the conductor rods to the electric fixture, said central post having an 60 elongated notched portion along one of its sides, a rod actuated pawl carried by said casing adapted to selectively engage said notches, whereby the electric fixture may be vertically adjusted, and an outer casing 65 surrounding the central post and the first-named casing in telescoping relation therewith.

WARREN W. POTTS.
